UNITED STATES PATENT OFFICE

FRANK L. LLOYD, OF BALTIMORE, MARYLAND, ASSIGNOR TO CROWN CORK & SEAL COMPANY, INC., OF BALTIMORE, MARYLAND, A CORPORATION OF NEW YORK

DESIGN FOR A BOTTLE

Application filed October 7, 1931. Serial No. 41,331. Term of patent 14 years.

To all whom it may concern:

Be it known that I, FRANK L. LLOYD, a citizen of the United States, residing at Baltimore, State of Maryland, have invented a new, original, and ornamental Design for Bottle, of which the following is a specification, reference being had to the accompanying drawings, forming a part thereof.

The dominant feature of the design consists in the configuration of the neck of the bottle.

I claim:

The ornamental design for a bottle, substantially as shown and described.

FRANK L. LLOYD.
